United States Patent Office.

PETER SCHOONMAKER, OF NEW BRITAIN, CONNECTICUT.

Letters Patent No. 80,510, dated July 28, 1868.

IMPROVED BIT FOR BRIDLES.

The Schedule referred to in these Letters Patent and making part of the same.

TO ALL WHOM IT MAY CONCERN:

Be it known that I, PETER SCHOONMAKER, of New Britain, in the county of Hartford, and State of Connecticut, have invented a new and improved Bit for Bridles, Harnesses, &c.; and that the following description, taken in connection with the accompanying drawings, hereinafter referred to, forms a full and exact specification of the same, wherein I have set forth the nature and principles of my said improvement, by which my invention may be distinguished from all others of a similar class, together with such parts as I claim, and desire to have secured to me by Letters Patent.

The present invention particularly relates to the "japanned bridle and harness-bits," so called and known in the trade, and it consists in providing the rings to such bits with a lining of German silver, or other metal having a bright surface, or susceptible of receiving and retaining a polish, whereby, while the beauty and finish of the bit-rings are much enhanced, the durability and wear of the japan are greatly increased.

In the accompanying plate of drawings my improved bit for harnesses and bridles, &c., is illustrated—
Figure 1 being a side view of a bit, having its rings lined according to the present invention.

Figure 2, a face view of one of the bit-rings.

Figure 3, a transverse section of one of the bit-rings, taken in the plane of the line $z z$, fig. 2; and
Figure 4, a section through the ring, in the plane of the line $y y$, fig. 1.

A, in the drawings, represents a bit, suitable for harnesses or bridles, and B its rings, one to each outer end, C, of the sections D of bit A, that are hung together at their other ends E. These rings B are hung in eyes F, to the bit-sections D, and all are japanned in any suitable manner.

The rings B, upon their inner sides or surface, are provided with a lining, L, of German silver, or other metal having a bright surface, or susceptible of being polished. This lining extends around the inner side of the said rings, and by its two ends, G, which are secured by being sprung into the slots α of the ring, at or near the eyes F, to the bit, and upon each thereof, as is plainly shown in the drawings, and fig. 4 more particularly.

The slots α may be sawed, cast, or otherwise formed in the bit-rings.

By providing a lining to the bit-rings, as above described, it is plainly obvious that not only are the durability and wear of the japan on the bit greatly increased, and other important advantages secured, but the appearance and beauty of the bit greatly enhanced, and thus a very desirable article of trade obtained.

Having thus described my improvement, what I claim as my invention, is—

As a new article of manufacture, a japanned bridle or harness-bit, having its rings lined with metal, substantially as described for the purpose specified.
